UNITED STATES PATENT OFFICE.

FREDERICK A. BAGNALL, OF ATTLEBORO, MASSACHUSETTS, ASSIGNOR TO GEORGE H. SYKES, OF ATTLEBORO, MASSACHUSETTS, AND GUSTAVE W. STRANDBERG, OF PROVIDENCE, RHODE ISLAND, COPARTNERS AS FIRM OF SYKES AND STRANDBERG, OF ATTLEBORO, MASSACHUSETTS.

DESIGN FOR A BRACELET-GUARD.

44,265.

Specification for Design.

Patented July 1, 1913.

Application filed February 17, 1913. Serial No. 749,051. Term of patent 3½ years.

To all whom it may concern:

Be it known that I, FREDERICK A. BAGNALL, a citizen of the United States, residing at Attleboro, in the county of Bristol and State of Massachusetts, have invented a new, original, and ornamental Design for Bracelet-Guards, of which the following is a specification, reference being had to the accompanying drawing, forming a part thereof.

The figure is a plan view of a bracelet-guard, showing my new design.

I claim:

The ornamental design for a bracelet-guard as shown.

In testimony whereof I have affixed my signature in presence of two witnesses.

FREDERICK A. BAGNALL.

Witnesses:

GEO. H. REMINGTON,
CHARLES C. REMINGTON.
